UNITED STATES PATENT OFFICE.

RUFUS BENNETT FOWLER, OF WORCESTER, MASSACHUSETTS, ASSIGNOR TO
THOMAS D. SAYLES, OF NORWICH, CONNECTICUT.

CARDING-ENGINE FOR MAKING MOTTLED YARNS.

SPECIFICATION forming part of Letters Patent No. 448,479, dated March 17, 1891.

Application filed May 3, 1882. Serial No. 60,337. (No model.)

To all whom it may concern:

Be it known that I, RUFUS BENNETT FOWLER, a citizen of the United States, residing at Worcester, in the county of Worcester and State of Massachusetts, have invented a new and useful Improvement in Carding-Engines for Making Mottled Yarns, of which the following is a specification.

My invention has for its objects to produce a machine which will furnish mottled yarn in which the two colors shall appear in alternate sections of short length and having the change from one color to the other abrupt and distinct, also to so interlace the fibers at the union of adjacent colors as to form yarn of uniform strength and tenacity; and my invention consists in the construction and arrangement of the actuating mechanism by which a nearly-instantaneous endwise movement is imparted to the doffer, with a succeeding period of "dwell," and also in the mechanism by which each of the reciprocating doffers is locked in position during its period of dwell.

The following specification contains a full, clear, and exact description of the same, reference being had to the accompanying drawings, in which—

Figure 1 shows a front elevation of a pair of "finisher-doffers" and their actuating mechanism, a portion of the main carding-cylinder being shown in the rear at A A. Fig. 2 shows a plan view of the same, the main cylinder being omitted and the frame A' being shown in section. Fig. 3 is an end view showing the locking device. Fig. 4 is a sectional view on the line x x, Fig. 1. Fig. 5 is a sectional view of the reciprocating mechanism on the line z z, Fig. 4; and Fig. 6 shows one of the driving-gears C.

Similar letters refer to similar parts in the several figures.

My invention is applied to the carding-machine known as the "finisher," and the general construction and operation of the several parts of the carding-machine do not vary from that in common use.

The "drawings" are fed in a horizontal layer in the usual manner, the wool being laid on the surface of the main carding-cylinder in parallel fibers and the drawings being arranged with the two colors in alternate strands.

The colors will appear upon the surface of the carding-cylinder in circumferential rings or zones 1 2, 1 2, 1 2, &c., Fig. 1.

The doffers B B³ are of the usual construction, save that they should be made as light as possible. The doffers are rotated by the pulley E, driven from the shaft of the main cylinder, pinion D, and gears C C.

It will readily be seen by reference to Fig. 60 1 that the rings of card-clothing upon the upper doffer will take the fibers of one color from the zones 1 1 1, and the rings on the lower doffer will take fibers of the other color from the zones 2 2 2. If the upper doffer be 65 moved to the right and the lower doffer to the left simultaneously the width of one of the rings, the upper doffer will then take the fibers from the zones of color 2 2 2 and the lower doffer from those marked 1 1 1, and by the 70 continued reciprocation of the doffers the roping will show the two colors on the main cylinder in alternate sections, the length of the sections depending upon the size and speed of the doffers and the frequency of the end- 75 wise movements thereof.

Mottled and clouded yarns have been heretofore made in different ways. In one the surface of the doffers has been constructed with alternate fixed and sliding strips, the 80 cards on the fixed strips taking one color from the main carding-cylinder and the cards on the sliding strips arranged in the proper plane of rotation to take the other color, the sliding strips being moved so as to bring the cards 85 into line with the cards on the fixed strips, as they come under the action of the wiper or doffer knife, producing a continuous roping in which the two colors appear in alternate section; but this method fails to sufficiently 90 interlace the fibers where the colors join, rendering the yarn weak.

Another method has been to arrange the rings on the doffers obliquely to the axis of the doffers, so the rings would take off two or 95 more colors at each revolution of the doffer; but this method, with the greatest practicable obliquity of the rings, renders the sections of color longer than is desirable, and between each section of clear color will occur a section, 100 with the colors mixed, which in many cases is objectionable.

I am also aware that clouded yarns have been made by reciprocating the doffers back and forth across the surface of carding-cylinders; but in all such cases the doffers have 5 been moved positively by cranks, eccentrics, or similar mechanical devices, and the motion of the doffers has consequently been slow and occurring but a few times during each revolution of the doffer, the result being the production of a yarn clouded, or with the colors more or less intermingled instead of mottled, or with constantly-repeating sections of each color, and the changes could only occur at 10 long intervals, owing to the slowness of the movement of the doffers.

My invention differs essentially from the above in the fact that I accomplish the change in the position of the doffer almost instantaneously by the recoil of a spring, reducing 15 the length of the section of yarn having the colors mixed to a minimum and allowing a long period for the dwell. I also use a locking device which securely holds the doffers in position during their period of rest, 20 and by the peculiar construction of the actuating mechanism I relieve the frame-work of the carding-engine from the concussion arising from so sudden a movement of the doffers, and the several results which characterize 25 my invention are produced by the peculiar actuating mechanism attached to the doffers, and constructed and operated as follows:

Journaled in suitable bearings in the frame A' A' is the shaft B', receiving its motion from 30 the shaft of the main cylinder, through the pulley C', pinion D', and gear E'. The shaft B' has the driving-gears F' F' and the broad-faced gear N. The frame A' A' also supports the sliding shafts H H', arranged as nearly as 35 may be in the same line as the shafts of the doffers B B³, to which they are attached by the joints V V. The actuating mechanism attached to each of the shafts H H' being alike, I shall confine my description to that 40 of the upper shaft H, which is shown in elevation in Fig. 1, in plan in Fig. 2, and in section in Fig. 5. The shaft H is held in sliding sleeves I I', which are supported in suitable bearings in the frame A' A'. Turning upon 45 the sleeves I I' and bearing against the inside of the frame are the pinions G G', driven by the gears F' F', and whose hubs form cams K K', which, pressing against the projecting pins J in the sleeves I I', draw the 50 sleeves inward, compressing the spring M, the sleeves I' being held from turning by the splines a, fixed to the frame and entering grooves in the sleeves. Similarly the sleeves I are prevented from turning by splines (not 55 shown) held in the frame A and entering grooves in the sleeves.

Attached to the sliding shaft H are the collars L and L', the collar L being placed against the end of the sleeve I and the collar L' being placed apart from the end of the sleeve I', as far as the desired "throw" of the doffer. L' has a groove in which the projecting end

of the spline a enters, keeping the collar and attached shaft from turning.

M is a spring held upon the shaft H, and 70 may be either a spiral spring coiled around the section of the shaft between the sliding sleeves, or, as shown in the drawings, an elliptic spring having holes through the central section of its leaves, through which the shaft 75 H passes. The tension of the spring M is applied to force the sliding sleeves I I' outward, holding their projecting pins J against the cams K K'. The cams K K' have a continuous rotary motion, as driven by the central 80 shaft B', through the gears F F' and G G', and the cams are so shaped that they act upon the sleeves I I' through their projecting pins as follows: About one-half of the rotation of the cam serves to draw the sleeve inward against the tension of the spring M, and the next half of the rotation of the cam holds the sleeve in a state of rest, then suddenly releasing the spring, which carries the sleeve 85 instantaneously outward, and the two cams 90 K K' are so placed upon the sleeves that they act alternately and at equal intervals in their action of sliding the sleeves against the tension of the spring M and in releasing the spring. It will be seen that the cams K K' 95 have no direct action upon the sleeves I I', except to draw them inward against the tension of the spring M.

In Figs. 1 and 2 of the drawings cam K is shown as having moved the sleeve I inward 100 and as holding it in a state of rest, while cam K' is engaged in moving the sleeve I' inward, and as the two cams continue their rotation the sliding motion of sleeve I' will be completed, and at the same time the pin J in the sleeve I will be released, allowing the tension of the spring M to push the sleeve I instantly outward, and as the sleeve I rests against the collar L the shaft H will be carried with it, also moving the connected doffer 105 B from color 1 1 1 to color 2 2 2. Sleeve I' is then held at rest while cam K is again moving sleeve I inward, when sleeve I' is similarly released, allowing the tension of the spring M to apply its force to the sleeve I', 110 moving it instantly outward, and as the sliding motion of the shaft H to the right, as already described, has brought the collar L' 115 against the end of sleeve I' the shaft H will be reversed, carrying the connected doffer B 120 to the left and again bringing its rings upon color 1 1. As the shaft H is moved by the sleeve I, resting against the collar L, the collar L' is brought against the outer end of the sleeve I', any momentum of the doffer and 125 connected parts which would tend to carry the doffer farther than the distance between the collar L' and the outer end of the sleeve I' will be resisted by the tension of the spring M, which thus not only serves to force the 130 doffer to the right, but also acts as a buffer to check the momentum of the doffer in its instantaneous movement, which would otherwise be received by the stationary portion of

the frame-work, causing an injurious jarring of the rigid parts of the machine. Similarly the momentum of the doffer as it is moved in the opposite direction is resisted by the impact of the collar L against the outer end of the sleeve I.

In order to allow the spring M to act as a buffer, as described, the cams K and K' should be cut away so that the pins J will not strike the cams as they are released before the collars L L' come in contact with the outer ends of the sleeves I I'. In this manner the continued reciprocation of the doffer is accomplished, a movement being effected to the right and left alternately at each half-revolution of the cams K and K', the spring M acting as the motive power to "throw" the doffer, and also serving as a buffer to gradually stop the doffer at the end of each throw, the dwell of the doffer being occupied by the cam which has last released its pin in again withdrawing its sleeve, and further compressing the spring M to accomplish the next throw of the doffer. The cams upon the lower shaft H' are so arranged that the motion of the two doffers B B' will be synchronous, but in opposite directions.

I am aware that doffers have been heretofore moved actuated by the tension of a spring. Such is done in the carding-engine forming the subject of the English Patent No. 502 of 1878, in which the doffer is moved positively in one direction by a cam, and on the reverse motion a spring is employed to hold the doffer against the cam, the conformation of the cam determining the movement of the doffer in both directions, whereas in the mechanism forming the subject of my present invention the doffer is moved by the tension of a spring in both directions, and the cams are only employed for the purpose of compressing the springs in advance of the required motion of the doffers. The doffers are also moved by releasing the spring from the action of the cam and thus producing an instantaneous motion of the doffer, and the same spring which is employed to move the doffer is also utilized to check its motion.

Running loose upon the end of the sliding shaft H, but held between collars L' and L' or shoulders on the shaft, is the pinion O, driven by the gear N, whose broad face provides for the lateral sliding motion of the pinion O and the shaft H. Upon the hub of the pinion O are two grooves P P, separated by the ring Q, the position of the grooves allowing the latch R to drop into one or the other of the grooves at the end of each throw of the doffer, holding it in proper position. The latch R turns upon the end of the shaft B', and is held in the grooves P P by the spring d, Fig. 3. The pinion O is driven at the same speed as the pinions G G' and cams K K', and the grooves P P are filled at opposite points in their periphery h h, Fig. 3, presenting a cam-surface which lifts the latch R out of the groove in time to allow the sliding motion of the shaft H. The

grooves P P should be a trifle wider than the latch R to permit the slight recoil of the doffer caused by the buffing of the spring M. 70

The locking device connected with the shaft H' is the same as that already described.

The frame supporting the actuating mechanism may be made a part of or connected with the frame-work of the carding-engine 75 and the proper alignment of doffer-shafts and sliding shafts secured; but in the construction shown the frame A' A' is detached, supported by the pillar b, and may be placed by the side of and connected with any ordinary 80 finisher-card.

In the first case an ordinary swivel-joint may be used to connect the shafts which will permit the rotation of the doffer-shafts. In the latter case I use the joints V V, which do 85 not require the exact alignment of the shafts. The collar S is fastened to the shaft H' and carries on its upper side the pin s. The collars T are fixed to the end of the doffer-shaft, embracing the loose ring t, which has lugs on 90 its upper side through which the pivot-pin passes, forming a hinge for the link t', through the opposite end of which the pin s passes, thereby connecting the two shafts, allowing the doffer-shaft to rotate and admitting of a 95 slight variation in the alignment of the shafts in both the horizontal and vertical planes.

Whenever it is necessary to take the doffers out for repairing or cleaning the cards, the link t' may be removed from the pin s. 100 The doffer-shafts slide through the hubs of the gears C C, the gears being held in position by the forked bar g, Fig. 6, inclosing the grooved hub f and attached to the frame of the card, rotary motion being imparted to the 105 doffers by means of the splines F F.

In the accompanying drawings I have shown only a small part of the frame of the carding-engine and a part of the surface of the main carding-cylinder A A, as the general construction and operation of a carding-engine embodying my invention does not vary from that in common use, except in those portions shown and described.

I do not claim the use of doffers having an 115 endwise reciprocating movement, as such have before been used; but

What I do claim, and desire to secure by Letters Patent, is—

1. The combination, with a carding-cylinder 120 and one or more doffing-cylinders having spaced rings of card-clothing, of sliding shafts with their axes substantially in alignment with the axes of said doffing-cylinders, springs whose tension is applied to move said sliding 125 shafts alternately in opposite directions with an instantaneous movement, and mechanism by which said springs are compressed and released, substantially as described.

2. The combination, with a carding-cylinder 130 and one or more doffing-cylinders, of actuating-springs whose tension is applied to move said doffing-cylinders in opposite directions alternately, and cams having a continuous ro-

tation and acting upon said springs to effect a gradual compression of the springs, followed by an instantaneous releasing of said springs, allowing their tension to be applied to said 5 doffing-cylinders, substantially as described.

3. The combination, with the doffers of a finisher-card, of the actuating mechanism consisting of the spring M, cams K K', sleeves 10 I I', with their projecting pins J, frame A' A', splines a a, collars L L', and shaft H, as described, and for the purposes set forth.

4. The combination, with the longitudinal-ly-reciprocating doffers of a finisher-card and mechanism for actuating the same, of a locking device consisting of the pinion O, with its grooved hubs P P and cams h and latch R, with spring d, as described, and for the purposes set forth.

5. The combination, with sliding shafts H 15 H', connected with the doffers of a finisher-card and their connected actuating mechanism and locking devices, as shown and described, of the driving shaft B', gears E', F'

F', and N, pinion D', and pulley C', as described, and for the purposes set forth. 25

6. The combination, with the rotary and longitudinally-reciprocating doffer-shafts, the sliding shafts H H', and their actuating mechanism, of the joints V V, consisting of the fixed collar S, with the pins, the fixed collars 30 T, the loose ring t, having lugs and pivot-pin, and the hinged connecting-link t', as described, and for the purposes set forth.

7. The combination, with a carding-cylinder and with one or more doffers and an actuating spring or springs M and mechanism for compressing and releasing said spring or springs, of shafts H H' and connecting-joints, substantially as described, between the shafts of the doffers and the shafts H H', substantially as described. 35 40
